FIG. 5.

Inventor
Charles W. Gross
14 by Robert W. Jenner,
Attorney

UNITED STATES PATENT OFFICE.

CHARLES W. GROSS, OF NAPA, CALIFORNIA.

RADIATOR.

Application filed December 14, 1920. Serial No. 430,639.

To all whom it may concern:

Be it known that I, CHARLES W. GROSS, a citizen of the United States, residing at Napa, in the county of Napa and State of California, have invented certain new and useful Improvements in Radiators, of which the following is a specification.

This invention relates to radiators for cooling water, which are used in connection with the internal combustion engines of automobiles, motor trucks, and other similar vehicles; and it consists in the novel construction and combination of the parts hereinafter fully described and claimed whereby the water for cooling the motor is brought in contact with and caused to circulate continuously through the tubes of the radiator, which are arranged zig-zag and which are cooled by contact with the air.

In the drawings, Figure 1 is a front view of a radiator constructed according to this invention. Fig. 2 is a side view of the same. Fig. 3 is a detail front view of one of the tubes drawn to a larger scale. Fig. 4 is a plan view of the tube shown in Fig. 3. Fig. 5 is a vertical section of a portion of the radiator showing one of the partitions and portions of the adjacent parts. Fig. 6 is a cross-section through one of the tubes, taken on the line 6—6 in Fig. 3.

A series of horizontal tubes or tubular units 8 is provided. Each tube is preferably rectangular in section, and is relatively wide horizontally in proportion to its vertical depth, but it may be of other approved form or cross-section. Rectangular chambers 9 are formed at each end of each tube, and are of greater depth than the tubes, so that when the tubes are superposed or stacked together upon their end chambers 9, horizontal air passages 10 are formed between them. The tubes and their end chambers are longer at their front sides than at their rear sides, so that the air passages 10 converge from front to rear, and collect the air as the motor car is moved forward.

A flat back plate 12 is secured to the rear side portions of the end chambers 9 when stacked together. Side plates 14 are provided, and have flanges 15 which overlap the back plates 12 and the front side portions of the end chambers 9. The end chambers of the tubes, and the plates 12 and 14 are all secured together by soldering their overlapping surfaces, or in any other ap-

proved manner. Vertical side chambers 16 are formed at the ends of the end chambers 9 by the plates 12 and 14, and these side chambers are triangular in cross-section. Each side chamber is divided into sections 60 by means of horizontal partition plates 17 which extend crosswise of them, and the partition plates of one side chamber are arranged in staggered relation to the partition plates of the other side chamber. In this 65 manner a zig-zag passage for cooling water is provided, and five or six tubes are usually connected with the section between each two adjacent partition plates.

An upper water chamber 20 having a 70 water inlet pipe 21 is arranged above the stacked tubes or tubular units, and communicates with one of the vertical side chambers. A lower water chamber 24 is arranged below the stacked tubes, and communicates 75 with the other vertical side chamber, and is provided with an outlet pipe 25. Water is circulated through the tubes and chambers in any approved way.

In order to increase the cooling effect of 80 the radiator, corrugated plates 28 of thin sheet metal are secured to the tubes 8 in the horizontal air passages 10. These plates 28 are cooled by contact with the inrushing air, and they also divide the air 85 into a multiplicity of very small streams which are more sure in action than larger streams.

Each partition plate 17 is soldered or otherwise secured between the adjacent surfaces of two end chambers 9 at one end, and its other end is secured to a narrow vertical plate 30 having flanges 31 which stiffen it and also form a means for securing it in place. The side plates 14 abut 90 against the plates 30 of the partitions, and the joints are kept water-tight in any approved way. The side plates or cover plates 14 can be removed, when desired, to give access to the tubes, without taking the 100 radiator to pieces. The various tubes or tubular units 8 can also be detached from each other, and removed and replaced without taking them all apart, and the number of them, and the number in each section, 105 can be varied according to circumstances, and so as to give the best results.

What I claim is:

1. In a radiator, a series of superposed tubular units, each unit being rectangular 110

in cross-section and relatively broad in proportion to its depth, said units having end portions which are deeper than their main portions and which are stacked one above another, thereby forming horizontal air passages between the said main portions, the said end portions being open at each end and the said main portions having flat and parallel upper and lower sides between the said end portions, and vertical side chambers secured over the ends of the tubular units and operating to distribute the cooling fluid to them.

2. In a radiator, a series of horizontal tubular units stacked one above another and having end chambers of greater depth than their main portions, said end chambers being open at each end and the main portions of the units between the end chambers having flat and parallel upper and lower sides and being longer in front than at the rear, and vertical side chambers secured over the open ends of the said end chambers and forming connecting passages with the units, for the circulation of cooling fluid.

3. In a radiator, a series of superposed tubular units, said units being rectangular in cross-section and longer in front than at the rear and having converging air passages between them, side chambers communicating with the ends of the said units, and partition plates extending crosswise of the side chambers and arranged in staggered relation, thereby forming with said

units and chambers a zig-zag passage for cooling fluid.

4. In a radiator, a series of tubular units having end chambers of greater depth than their main portions, said tubular units being longer in front than at the rear, and said end chambers being secured one above another so that air passages are formed by and between the said main portions, and side chambers communicating with the said end chambers, said side chambers being triangular in cross-section and forming with the tubular units passages for cooling fluid.

5. In a radiator, a series of tubular units having end chambers of greater depth than their main portions, said tubular units being longer in front than at the rear, and said end chambers being secured one above another so that air passages are formed by and between the said main portions, back plates secured to the rear side portions of the said end chambers, and side plates arranged opposite the ends of the tubular units and secured to the said back plates and to the front side portions of the said end chambers, said back plates, side plates and end chambers forming side chambers which are triangular in cross-section and which form with the tubular units passages for cooling fluid.

In testimony whereof I have affixed my signature.

CHARLES W. GROSS.
